UNITED STATES PATENT OFFICE.

RAMON CAMELL, OF RHÔNE, AND LAURENT COCHET AND JOSEPH GRITTE, OF LYON, FRANCE, ASSIGNORS TO SOCIETE LYONNAISE DES RICHAUDS CATALYTIQUES, CAMELL, COCHET, GRITTE & CIE., (SOCIETE EN COMMANDATE,) OF RHÔNE, FRANCE.

APPARATUS FOR HEATING BY CATALYSIS.

1,379,742.

Specification of Letters Patent. Patented May 31, 1921.

Application filed May 26, 1919. Serial No. 299,784.

To all whom it may concern:

Be it known that we, RAMON CAMELL, chemist, of St. Rambert l'Ile-Barbe, Rhône, France, a citizen of the French Republic, 5 LAURENT COCHET, manufacturer, of Lyons, France, a citizen of the French Republic, and JOSEPH GRITTE, manufacturer, of Lyons, France, a subject of the King of Belgium, have invented certain new and useful Im- 10 provements in Apparatus for Heating by Catalysis, of which the following is a specification.

This invention relates to catalytic heating apparatus, and consists broadly in the for- 15 mation of projections on the radiating surface of the platinated asbestos principally in order to increase the heating area.

In the accompanying drawings,

Figure 1 shows the application of the 20 invention to a heating apparatus placed on a known type of lamp *b*. Fig. 2 illustrates the invention applied to a heater with horizontal vapor supply. Fig. 3 illustrates the invention applied to a smoothing iron. Re- 25 ferring to Fig. 1, the cushion or carpet of asbestos *a* presents, on its upper surface bosses *a*¹ or other designs, such as undulated or spindle-shaped embossing, of any ar- 30 rangement and shape, for the purpose, on the one hand, of facilitating the inflammation of the spirit vapors when the apparatus starts working and, on the other hand, of increasing the active radiating surface of the apparatus and consequently its heating 35 power.

In this arrangement the metal tube *c* passes through the carpet of asbestos at its base, and it contains, near its lower part, openings *c*¹ to allow the evaporation and 40 outlet of the spirit. One of the bosses may be provided at the center of the catalyzing carpet. By raising the wick which passes inside the tube *c*, the latter may be brought into contact with the platinated asbestos, 45 thus at once allowing the spirit to rise by capillarity into the asbestos through the un- covered surface of said wick. A light may be applied to the said central boss, so as to bring the heater into activity. At the end 50 of some minutes, the flame will be extin-

guished of itself, the wick should then be lowered again.

According to the arrangement of the ap- 55 paratus, the tube *c*, instead of being vertical can also be horizontal, as shown in Fig. 2, in order to enable spirit to be supplied.

Fig. 3 represents a box-iron heated by catalysis. The necessary heat is supplied to it by a catalyzing carpet *a*, with bosses on the lower surface which, in a smoothing 60 iron is the radiating surface. One or more perforations *g*¹ in the mass of iron which forms the "iron" allow the air to feed oxygen to the carpet. The spirit reservoir *b*¹ being placed above, in order to prevent the liquid 65 spirit from dropping on the catalyst— which would stop the catalysis—a special device should be employed. This device consists in a tube *h* secured to the reservoir *b*¹ and containing a wick which descends 70 down to *h*¹ and rises in the bottom of the reservoir up to *h*²; surrounding this first tube there is another *i* of smaller diameter, closed at *i*¹ and perforated at *i*². Between the two tubes carded asbestos serves as wick 75 and sucks up by capillary attraction the spirit brought by the wick, which then evap- orates through the opening *i*².

What we claim as our invention and de- 80 sire to secure by Letters Patent of the United States is:—

1. In a catalytic heating apparatus, a cat- 85 alytic pad so formed that the radiating sur- face is undulatory, and means for supplying inflammable vapor to said pad.

2. In a catalytic heating apparatus, a cat- 90 alytic pad, the radiating surface of which is formed with a plurality of bosses, and means for supplying inflammable vapor to said pad.

In witness whereof we have signed this 95 specification in the presence of two wit- nesses.

RAMON CAMELL.
LAURENT COCHET.
JOSEPH GRITTE.
